W. C. STANLEY,
AUTOMATIC GAS CONTROL.
APPLICATION FILED JUNE 10, 1918.

1,282,135.

Patented Oct. 22, 1918.

UNITED STATES PATENT OFFICE.

WALTER C. STANLEY, OF WILLOUGHBY, VERMONT.

AUTOMATIC GAS CONTROL.

1,282,135.

Specification of Letters Patent. Patented Oct. 22, 1918.

Application filed June 10, 1918. Serial No. 239,147.

To all whom it may concern:

Be it known that I, WALTER C. STANLEY, a citizen of the United States, residing at Willoughby, in the county of Orleans, State of Vermont, have invented certain new and useful Improvements in Automatic Gas Controls; and I do hereby declare the following to be a full, clear, and exact description of the invention, such as will enable others skilled in the art to which it appertains to make and use the same.

This invention is an improvement in gas burners and has particular reference to an automatic cut-off device therefor.

An object of the invention is to provide an improved device which is automatically operated to positively close the stop cock or valve in a gas supply pipe should the gas flame of a burner become extinguished by blowing the same out or otherwise, thus providing a safeguard against explosions or asphyxiations.

Another object is the provision of a device of this character which is simple in construction, easy to manufacture, readily applicable to gas fixtures and other burners and effective in carrying out the purpose for which it is designed.

The inventive idea involved is capable of receiving a variety of mechanical expressions one of which, for the purpose of illustrating the invention, is shown in the accompanying drawing wherein:—

Figure 1 is a side elevation of the device showing the same applied to a gas fixture.

Fig. 2 is a fragmentary view similar to Fig. 1 showing the position of parts immediately following the manual adjustment of the stop cock to opened position and the lighting of the gas flame.

Fig. 3 is an enlarged fragmentary vertical sectional view.

Fig. 4 is a perspective view of the lever attached to the stop cock.

Fig. 5 is a similar view of the rod associated with the lever.

In the drawing, the numeral 10 indicates the vertical pipe of a gas fixture through which the gas is fed to the branch pipe 11 carrying the usual gas tip upon its free end and to which the gas is fed by means of the usual stop cock or valve 12 which controls the flow of gas through the pipe 11.

The cut-off or control device which comprises the essential feature of the invention

is shown in what is now believed to be its preferred form which consists of a horizontal supporting bracket or arm 13 having one end secured to the pipe 10 and maintained in its supporting position by means of the diagonal brace 14 also secured to said pipe and to the arm adjacent its outer end. A thermostatic element or vessel 15 is supported by the arm or bracket 13 and is provided upon its upper surface with a pair of upstanding lugs 16 which receive the outer end of the arm 13 therebetween whereby the element 15 may be secured thereto. Inwardly from the thermostatic element 15, the arm 13 has secured thereto the upper end of a fulcrum arm 17 arranged in a vertical position and having its lower end bifurcated as indicated at 18 to receive the intermediate portions of a lever 19 which is pivoted in said bifurcation as indicated at 20. This lever or rocking element is pivotally connected, at one end, to the depending lugs 21 of the thermostatic element 15 and is pivoted, at its other end, to a coupling 22 which has a screw threaded opening to receive the upper end of a depending arm or rod 23 whereby a pivotal connection will be established between said arm or rod and the rocking element 19. The lower end of the rod 23 is bent slightly as indicated at 24 and extending through said rod in a diagonal direction with respect thereto is a pin 25 which projects downwardly to form an acute angle with the rod.

The stop cock 12 has associated therewith a lever 26 bifurcated in one end to receive said stop cock and attached thereto by means of small bolts 27, the other end of the lever 26 being beveled as indicated at 28. The lever 26 is further provided adjacent the beveled end thereof with a slot 29 for receiving the lower end of the rod 23 and also for receiving the pin 25 when the lever is adjusted to a position to permit of the gas being lighted.

In practice, when the parts are in the position shown in Fig. 1, the stop cock 12 is closed and the flow of gas through the pipe 11 prevented. In this position, the lower end of the rod 23 extends into the slot 29 in the lever 26 while the pin 25 engages the beveled end 28 of said lever, this also being the position of the parts when the lever 26 has been automatically adjusted to close the stop cock 12. When it is desired to light

the burner a slight upward pressure upon the lower end of the rod 23 is exerted thereon to disengage the pin 25 from the beveled end 28 whereby the lower end of said rod 5 may be swung slightly to the right, as shown in the drawing, and the lever 26 may then be swung upwardly to open the stop cock 12 and in this movement, the rod 23 will remain stationary, the pin 25 thereof passing into the slot 29. After the flame has been lighted 10 the heat thereof will expand the thermostatic element 15 and thus rock the end of the lever 19 attached thereto in a downward direction with the result in that an upward pull will be exerted upon the rod 23 and as soon as the 15 lower end of the pin 25 is disengaged from the slot 29 said rod will swing back to its normal position with only the lower end 24 thereof engaged in the slot. Now should the 20 flame through any reason become extinguished without turning off the stop cock 12 the cooling of the element 15 will cause a contraction thereof which will operate the lever 19 in the opposite direction to exert a 25 downward pressure upon the rod 23 whereupon the pin 25 will again engage the beveled end 28 and force the lever 20 downwardly to turn the stop cock 12 to its closing position and in this manner the automatic 30 prevention of any flow of gas through the pipe 11 will be effectively executed.

What is claimed is:—

In a device of the character described, the combination with a gas supply pipe and a stop cock for regulating the flow of gas 35 therethrough, of a thermostatic element situated in proximity to said gas pipe whereby the heat of the flame from said pipe will cause an expansion of said element, a rocking element actuated by the expansion and 40 contraction of said thermostatic element, a lever secured at one end to said stop cock and provided with a longitudinal slot adjacent its other end, a rod pivoted to said rocking element and depending therefrom and 45 having its lower end positioned within said slot, and a pin carried by said rod and engageable with free end of said lever to move the same to a closing position when said thermostatic element contracts, said pin being adjustable into said slot to permit of a swinging of said lever to a position to open the stop cock and being also movable, by 50 gravity, to its operative position in engagement with the end of said lever upon the expansion of said thermostatic element.

In testimony whereof, I affix my signature, in the presence of two witnesses.

WALTER C. STANLEY.
